J. R. MERCER.
FOLDING SEAT FOR JUVENILE VEHICLES.
APPLICATION FILED SEPT. 1, 1917.

Patented Mar. 19, 1918.

FIG. 3.

INVENTOR
James R. Mercer,
By *Own, Own & Crampton,*
His atty.

UNITED STATES PATENT OFFICE.

JAMES R. MERCER, OF TOLEDO, OHIO.

FOLDING SEAT FOR JUVENILE VEHICLES.

1,260,235.

Specification of Letters Patent. Patented Mar. 19, 1918.

Application filed September 1, 1917. Serial No. 189,277.

To all whom it may concern:

Be it known that I, JAMES R. MERCER, a citizen of the United States, and resident of Toledo, in the county of Lucas and State 5 of Ohio, have invented a certain new and useful Folding Seat for Juvenile Vehicles; and I do hereby declare the following to be a full, clear, and exact description of the invention, such as will enable others skilled 10 in the art to which it appertains to make and use the same, reference being had to the accompanying drawings, and to the characters of reference marked thereon, which form a part of this specification.

15 This invention relates to folding seats, and more particularly to a seat of this character adapted for use in juvenile push-wagons.

20 The object of my invention is the provision of a seat of the class described, which is simple and inexpensive in its construction and adapted when not in use to be folded up below the top surface plane of the wagon-box floor and to form a part of such 25 floor, and when in use to be raised to form a seat in elevated relation to the box.

The invention is fully described in the following specification, and while, in its broader aspect, it is capable of embodiment 30 in numerous forms, a preferred embodiment thereof is illustrated in the accompanying drawings, in which—

Figure 1 is a side elevation of a juvenile wagon embodying the invention with the 35 seat in raised position. Fig. 2 is a fragmentary longitudinal section of the box portion thereof with the seat in full and in raised position, and Fig. 3 is a similar view with the seat in full and in closed or folded 40 position.

Referring to the drawings, 1 designates the box of a juvenile push-wagon, the bottom 2 of which is provided with an opening 3. The under side of the wagon bottom 45 is provided at the front and rear edges of the opening 3 with cross-pieces or beams 4 and 5, respectively, and the bottom edges of these cross-pieces have inwardly projecting flanges 6.

50 A seat-support 7, which may constitute a single broad or board-like post member, is hinged at its rear end to the rear cross-piece 5, as at 8, and is adapted to have swinging movements through the opening 3 and 55 when in folded position to rest at its front and rear ends on the respective flanges 6, 6,

with its top surface below the plane of the under side of the box bottom. The free or forward end of the support 7 is provided with one or more seat engaging tenons 9. 60

The seat comprises the front upright or supporting member 10 and the horizontal seat member 11, which are hingedly connected at their adjacent edges for folding movements one over the other. The upright 65 member 10 is hinged at its lower edge to the front cross-piece 4, as at 12, to adapt it to rest in horizontal or reclining position over the support 7 in a plane immediately below the plane of the under side of the box bottom 2. When the upright 10 is in such folded position the seat member 11, which is hinged to the upright 10, as at 13, extends 70 forward from the rear edge of the member 10 in filling relation to the opening 3 of the 75 box bottom, thus forming a portion of such bottom. The seat member 11 is provided with openings, not shown, into which the tenons 9 fit when the seat is in raised or usable position, as shown in Fig. 2. 80

It is evident that the seat practically comprises only three members, namely, the standard 7, upright 10 and seat member 11 and that when the seat is in folded position said three members lie in a horizontal plane 85 one over the other in the order given, with the seat member 11 forming the closure for the opening 3 in the box bottom. It is also evident that the seat is capable of being easily and quickly folded or unfolded and 90 that when in unfolded or usable position it forms a rigid and practical seat on which the user of the wagon may sit as he pushes the wagon along with one foot. 95

While the invention is particularly described for use in connection with a juvenile wagon it may also be used in connection with other wagons or similar vehicles.

I wish it understood that my invention is not limited to any specific construction, 100 arrangement or form of the parts, except in so far as such limitations are specified in the claims.

Having thus described my invention, what I claim as new, and desire to secure by Letters Patent, is—

1. The combination with a wagon-box having an opening in its bottom, of cross-supports provided on the under side of the box bottom at the front and rear edges of 110 said opening, and a seat comprising front and rear upright members and a seat mem-

ber supported by said upright members and all foldable through said opening one over the other between said cross-pieces and supported thereby, with the rearmost member, when folded, resting directly on the supports.

2. The combination with a wagon - box having an opening in its bottom, of supporting members secured to the under side of the box adjacent to the front and rear edges of said opening, a support hinged to lie between and be supported by said front and rear members and to be raised through said opening to upright position, a front upright member and a seat member hinged together and to the under side of the bottom adjacent to the front edge of said opening for folding movements one over the other in and below said opening and upon said support when in folded position, said support when in raised position adapted to engage and support the seat member in its raised position.

3. The combination with a member having an opening therein, of a seat comprising

ing two supports hinged adjacent to opposite side walls of said opening for folding movements one over the other, and a seat member hinged to one of said supports for folding movements thereover and adapted when in raised position to rest on the other of said supports when in its raised position and when in folded position to lie over the supports within said opening.

4. The combination with a bottom member having an opening therein, of front and rear supports hinged adjacent to opposite walls of said opening in planes one above the other, and a seat member hinged to the free edge of one of said supports and adapted to releasably engage the other of said supports whereby it is held in raised position thereby, said supports and seat member when in folded relation lying in reclining position one over another in said opening with the seat uppermost.

In testimony whereof, I have hereunto signed my name to this specification.

JAMES R. MERCER.
